UNITED STATES PATENT OFFICE.

CLAUDE A. McGINNIS, OF ATLANTA, GEORGIA, ASSIGNOR TO BOWMAN-DOZIER MANUFACTURING COMPANY, OF ATLANTA, GEORGIA, A CORPORATION OF GEORGIA.

FIREPROOF WINDOW-FRAME.

961,729.

Specification of Letters Patent. Patented June 14, 1910.

Application filed April 17, 1909. Serial No. 490,514.

To all whom it may concern:

Be it known that I, CLAUDE A. McGINNIS, citizen of the United States, residing at Atlanta, in the county of Fulton and State 5 of Georgia, have invented certain new and useful Improvements in Fireproof Window-Frames, of which the following is a specification, reference being had therein to the accompanying drawing.

10 The principal object of this invention is to provide a comparatively light and inexpensive window that shall be practically fireproof, under ordinary conditions, that is, be capable of resisting safely fire within or 15 without when the window is raised to incandescence and so maintained for a long time, and even when it is suddenly cooled by the application of water from a hose or otherwise. With this object in view the window frame 20 and sash are so made from sheet metal that neither heating nor cooling can cause serious opening of seams or distortion of parts. With metal parts so constructed I adopt the well known expedient of using glass in 25 which fine-mesh wire is embedded, so that the glass resists impact of water and is held in place although shattered.

Minor objects are to provide for ready access to weight pockets and for repairing 30 any injury to the pulleys for the chains or cables carrying the weights.

In the drawings, Figure 1 shows in elevation the interior face of a window. Fig. 2 is a section on the line 2-2, Fig. 1. Fig. 3 is a section of the frame, on line 3-3, Fig. 1. Fig. 4 is a side elevation of a portion of a jamb, showing the pocket section. Fig. 5 is a section on the line 8-8, Fig. 4. Fig. 6 is a bottom plan view of one end of the head 40 jamb. Fig. 7 is a vertical section on the line 11-11, Fig. 6.

It is to be observed that the sill, and sides of the frame, are each made from a one-piece sheet of metal bent on parallel lines 45 only, and that the top member of the frame is similarly made, except that for convenience the upper plate thereof is made to slide into locking engagement with the two face walls of that member.

50 The sill member A has at its lower outer angle a doubled flange A', is provided at A², just below the inner sash with a groove over which a lip of the sash projects, and rises at A³ just within the sash. From this raised 55 portion the web descends vertically to meet

the lower web at the lower inner angle of the sill, where the two marginal portions are interlocked as seen at A⁴. The side members or jambs of the frame, as seen in Fig. 3, are bent to form a stop 60 B, a recess for a parting bead B', a recess for a removable stop B², and flanges B³, B⁴ at the outer angles of the frame, the margins of the constituent sheet being interlocked at the latter flange. The stop B and 65 bead are each provided with a lateral groove B⁵ each to be engaged by a lip upon the corresponding sash. These members have their ends so cut that their inner walls partly fit upon, partly enter, apertures in the sill 70 while the remaining walls extend over the sill to which they are united by rivets or bolts B⁶, Fig. 1. To permit access to the weights the inner walls are cut away as indicated in Figs. 4, 5, and the opening is 75 closed by a plate B⁷ which is bent like the part removed, but has one margin bent to pass within the jamb and engage like a hook 80 B⁸ with the lateral rib formed in the stop B by its lateral groove, while the opposite margin B⁹ overlaps the jamb in the recess for the outer stop B². The bead and stop are 85 held in place by screws engaging plates B¹¹ (Fig. 4) fixed in the recesses. The lower wall of the upper member of the frame is 90 bent to form ribs C, C', C² registering with the stop B, bead B' and stop B², respectively, of the side members, and is further 95 bent to form a narrow groove C³ to receive a lip upon the upper sash. The vertical face 96 walls of this member, bent sharply outward and tied together by a top plate C⁴, are overlapped, like the sill, by the side frame members and united therewith by rivets or bolts C⁵. The pulleys C⁶ are carried by this upper member, each set being mounted upon a removable plate C⁷ fitting an opening in the lower wall of the member, or head jamb, resting directly upon the upper end of the side jamb, and held by screws C⁸ which engage a heavy plate C⁹ rigidly fixed to the concealed face of the jamb and extending over the opening. At each side of the opening the metal of the jamb is bent upward to 100 form vertical flanges C¹⁰, and the plate is 105 formed with ears C¹¹ to support the pulley shaft C¹². The plate projects over and normally rests upon the upper end of the side jamb in such position that the chain passing 110 over the pulley and down to the sash lies

near the jamb, as usual, while the other fold of the chain, carrying the counterbalancing weight, hangs at some distance from the opposite face of the jamb. Obviously, the 5 weight of the sash and counterbalance is thus borne by the jamb and there is no strain upon the plate retaining screws. The bead or strip B' and the screws C' being removed, the pulley plate may be conveniently re- 10 moved, with its pulleys, and replaced without disturbing other parts the inner end of the plate being swung downward while the outer end is raised and the plate being then moved longitudinally inward and down- 15 ward. To facilitate engaging the plate for this purpose, apertures C²⁰ therein may be provided.

The bead or strip B' and the stop B², owing to their being confined in the recesses 20 cannot spread when heated, and the stop, being more exposed, is provided with a double lip B¹² and with a web B¹³ to prevent this lip from moving toward the opposite wall of the recess when heated.

25 It is to be noted that the jamb has its outer stop integral, and that both the remaining stops lie partly between the sash and jamb so that the sash protects them and aids in holding them in place; that the salient portions of the jambs enter openings in the sill and head; that the upper sash helps to protect and hold the pulley plate, while its lip entering a recess in the head jamb excludes air and prevents the central part of 30 the sash from bending when heated; that the pocket plate is held and protected by the stops and lower sash; that the lip on the lower sash rail shutting over the offset in the sill prevents inward curvature as well as excludes air; that the curved offset in the sill turns entering air outward, and that the inner offset of the sill holds the inner side of 35 the rail.

40 It is especially important that each of the main frame members is formed from a single sheet by successive bending on parallel lines, being first cut to exact form and suitably perforated by dies.

45 What I claim is:

50 1. The combination with a sheet metal window frame having in its side members or jambs recesses in position to be partially overlapped, laterally, by the lateral edge faces of a sash in normal position in the 55 frame, of stops each in position to engage the inside face of the corresponding sash and each having a base adapted to extend between the edge face of the sash and the bottom of the corresponding recess.

60 2. The combination with a sheet metal window frame having its side or jamb mem-

bers each bent to form an integral outer sash stop and a recess in position to be partially overlapped and covered by the lateral edge face of the sash, of a stop adapted to 65 engage the inside face of the sash and having a broad base portion in position to extend between said edge face and the bottom of the corresponding recess.

3. The combination with a sheet metal 70 window frame having its side body members provided with integral, laterally grooved sash stops and cut away to form openings to the pockets, of plates, for closing said openings, having one lateral margin entering the body members and in hooked engagement with one of said stops and its other lateral margin overlapped upon the body member in position to be held by an inside removable stop. 80

4. The combination with a sheet metal window frame having hollow side members cut away to form an opening extending across both sash spaces, of a closing plate for said opening bent into conformity with 85 the jamb wall above and below the opening.

5. A sheet metal window sill having its inclined upper wall bent upwardly and forwardly upon itself and then sharply rearwardly parallel to its original direction, to 90 form below the place of the lower sash and just within the plane of its outer face an upward offset having an outer face adapted to reverse the current of incoming fluid and direct it against the usual sash lip projecting over the offset against the body of the sill. 95

6. The combination with a sheet metal window frame having in its side jamb faces which are adjacent to the edges of the sash 100 longitudinal recesses adapted to be covered in part by the edge faces of the sash, of stops having broad bases filling said recesses from side to side, respectively, and provided with narrower longitudinal salient portions 105 adapted to overlap the broader face of the sash, substantially as set forth.

7. The combination with a sheet metal window frame having stop-receiving grooves, of 110 sheet metal stops having laterally projecting bases which are flush with the jambs and themselves have lateral marginal flanges projecting to the bottoms of the grooves, and means for detachably securing the stops in 115 their grooves.

In testimony whereof I affix my signature in presence of two witnesses.

CLAUDE A. McGINNIS.
